DESIGN FOR A COOKING POT OR SIMILAR ARTICLE

Alfred C. Rantsch, Toledo, Ohio, assignor to The Bellaire Enamel Company, Bellaire, Ohio, a corporation of Ohio

Application May 21, 1935, Serial No. 56,936

Term of patent 7 years

To all whom it may concern:

Be it known that I, Alfred C. Rantsch, a citizen of the United States of America and resident of Toledo, county of Lucas, and State of Ohio, have invented a new, original, and ornamental Design for a Cooking Pot or Similar Article, of which the following is a specification, reference being had to the accompanying drawing, in which—

Figure 1 is a top plan view of a cooking pot
showing my new design;

Figure 2 is a side elevational view of the same;
and

Figure 3 is a vertical sectional view taken on line 3—3 of Fig. 1.

I claim—

The ornamental design for a cooking pot or similar article, substantially as shown.

ALFRED C. RANTSCH.
